UNITED STATES PATENT OFFICE

110,030

DESIGN FOR A BOTTLE

Harry Lilienthal, New York, N. Y.

Application April 8, 1938, Serial No. 76,378

Term of patent 14 years

To all whom it may concern:

Be it known that I, Harry Lilienthal, a citizen of the United States, residing at 27 West 72nd Street, city, county, and State of New York, have invented a new, original, and ornamental Design for a Bottle, of which the following is a specification, reference being had to the accompanying drawing forming part thereof.

Figure 1 is a front view;

I claim:
The ornamental design for a bottle as shown.
HARRY LILIENTHAL.
